(57) **CLAIM**

The ornamental design for a container sleeve with storage pockets, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front elevation view of a container sleeve with storage pockets with the strap removed, showing my new design;

FIG. 2 is a rear elevation view thereof;

FIG. 3 is a right side elevation view thereof;

FIG. 4 is a left side elevation view thereof;

FIG. 5 is a top plan view thereof;

FIG. 6 is a front, right, top perspective view thereof;

FIG. 7 is a rear, left, bottom perspective view thereof; and, FIG. 8 is a front, right, bottom perspective view thereof, with the strap attached.

The trademark material “H2O Capsule” printed on the strap of FIG. 8 forms part of the claimed design. The owner of the registered trademark is Blakestone US LLC.
